UNITED STATES PATENT OFFICE

119,255

DESIGN FOR A PLAQUE OR SIMILAR ARTICLE

Gildo Capellazzi and Vincent Germana,
Brooklyn, N. Y.

Application December 2, 1939, Serial No. 88,636

Term of patent 3½ years

To all whom it may concern:

Be it known that we, Gildo Capellazzi and Vincent Germana, both citizens of the United States, and residents of Brooklyn, New York, in the county of Kings and State of New York, have invented a new, original, and ornamental Design for a Plaque or Similar Article, of which the following is a specification, reference being had to the accompanying drawing, forming a part thereof, and in which Figure 1 is a view in front elevation of a plaque or similar article showing my new design; Fig. 2 is a view thereof in side elevation; Fig. 3 is a top plan view thereof; Fig. 4 is a vertical sectional view thereof on line 4—4 of Fig. 1; and Figs. 5, 6, 7 and 8 are sectional views thereof on the lines 5—5, 6—6, 7—7, and 8—8, respectively, of Fig. 1.

I claim:

The ornamental design for a plaque or similar article substantially as shown.

GILDO CAPELLAZZI.
VINCENT GERMANA.
